UNITED STATES PATENT OFFICE

SEYMOUR TROY, OF NEW YORK, N. Y.

SHOE CONSTRUCTION

Application filed September 27, 1930. Serial No. 484,808.

This invention relates to shoe constructions and particularly to constructions for shoes of the turned variety.

The invention has for its object an improved construction and arrangement of parts for shoes of the character described, which is strong, durable, efficient and readily manufactured.

More specifically, an object of the invention is to provide an improved construction for soles in turned shoes whereby the uppers may be sewed on to the ball, shank and seat parts in a durable and secure manner without liability to excessive stresses in the parts.

It is also an object to provide a sole construction in which the ball and seat parts are united by a relatively long, narrow shank to which the uppers are stitched from opposite sides by means of an interlocking stitch.

Other objects of the invention will in part be obvious and will in part appear herein-after.

The invention accordingly comprises the features of construction, combinations of elements, and arrangement of parts, which will be exemplified in the constructions herein-after set forth and the scope of the application of which will be indicated in the claims.

For a fuller understanding of the nature and objects of the invention, reference should be had to the following detailed description taken in connection with the accompanying drawing, in which:

Fig. 1 is a fragmentary view, mainly in section, showing the construction in a vertical plane, of a lady's shoe of the turned variety, embodying the present invention;

Fig. 2 is a plan view of the sole construction employed in Fig. 1, the upper being cut away;

Fig. 3 is an enlarged fragmentary view showing the shank portion of the sole illustrated in Fig. 2 and depicting more in detail the interlocked stitch employed;

Figs. 4 and 5 are fragmentary sectional views taken along the lines 4-4 and 5-5 respectively, in Fig. 3.

Referring now to the drawing and particularly to Fig. 1, 10 denotes generally a sole having a ball portion 11, to which an upper

12 is stitched in the usual manner, the sole also having a shank portion 13, which extends rearwardly and merges into an enlarged or seat portion 14, to which a heel 15 is attached in the usual manner. The hind quarter 16 of the upper here illustrated is secured to the rear portion of the sole independently of the front upper. While this construction is convenient in the type of lady's shoe here illustrated, it is by no means essential and comprises no part of the present invention. The hind quarter 16 envelopes a counter 17 that is sewed on to the sole, together with the usual lining, indicated at 18. The front upper also preferably has a lining as indicated at 18'. 55 60 65

In accordance with the practice of the present invention, the sole is blanked out from any suitable sole material, for example, from oak-tanned full leather, and is shaped to have a form adapted to have the uppers secured thereto by stitching, the shank being shaped to afford an interlocked stitch without the use of channels, as more fully is explained hereinafter. A suitable shape is shown in Fig. 2 where the ball 11 is of the usual shape 70 75 and is provided with channels 20 and 21 cut around each side of the same, these channels converging and ending at a point 22, where the shank ordinarily merges into the ball. The rear or seat portion 14 of the sole is similarly formed and has a channel 23 running around its edge in a generally oval or elliptical contour converging toward a point 24, where the shank joins the seat. Thus it 80

is seen that the channels are not cut into the shank portion 13 of the sole here employed, thereby providing a connecting piece for the front and rear portions of the sole which does not have its strength impaired. The shank is also relatively narrow so that the stitch employed may extend from one side of the shank up through its central portion thereof; the stitching from the other side being made to overlap and interlock with the stitching from the first side. The general manner in which this stitching is accomplished is seen in Figs. 3, 4 and 5 and avoids the through stitch from side to side that otherwise would tend to split the shank portion. 90 95

The shank portion 13 is here constructed 100

so as to be relatively long and narrow and extends in a direction so as to support the outside of the human foot, and so is not placed so as to extend centrally under the arch of the foot. This involves a somewhat offset positioning of the shank relative to the ball, which stitched to the upper, imparts a relatively high degree of strength. The gradual widening of the shank heretofore employed 10 where the shank merges into the ball is here avoided; the shank being here connected with the ball by a contour which meets the latter rather abruptly on either side as indicated at points 25 and 26.

15 While the shank is joined onto the ball rather abruptly, it is preferable to avoid sharp angles in shaping the seat so as to join with the shank. To this end a generally oval or elliptical form of seat is shown as merging 20 with the shank. The sole when thus shaped and channeled is provided with the usual peripheral groove, here shown at 27, and is then ready to have the upper sewed thereon in the usual manner. The upper is 25 stitched to the sole, shown in Fig. 2, with its reverse side out. A lock stitch, such as indicated in broken lines at 28, is preferably employed to secure the margin of the uppers in 30 the peripheral groove by stitching about the edge of the ball through to the base of the channel.

Assuming that the stitching operation is to take place, the stitch starts at some convenient point on the sole, for example, adjacent 35 the numeral 28 in Fig. 2, and proceeds in a counter-clockwise direction about the ball of the sole until the end of the channel is reached at 22. A passage for the stitch is now cut by a curved shoemaker's awl through 40 a side of the shank and made to come out through an opening near the centre of the top, as indicated at 29 in Fig. 3. The stitch is then looped over through an adjacent central hole 30, with the other portion of the 45 lock-stitch until the upper is completely sewed on to one side of the shank. The last stitch depicted in Fig. 3 of this character enters a hole at 31, which is substantially at the point 24, where the channel converges 50 that is formed in the seat.

When the channel in the seat is reached, the stitching of the rear portion of the upper, including the counter to the sole, is continued in the usual manner; the lock-stitch effecting 55 this being shown in broken lines at 32. When the stitching returns to the point 24 from the other side of the seat, the subsequent stitches are made to interlock with those first taken through the shank. The stitch which 60 is next taken at this point is shown as inserted up through a curved opening, the thread coming out through a hole at the top, here denoted 33; the next stitch indicated at 34 being looped under and about the ends 65 35 and 36 of the adjacent stitched loops taken

from the other side. In this manner, the interlocking loops as shown at 37, 38 and 39, etc., are provided.

The resulting structure of the shank with the uppers sewed thereto, is depicted in cross section in Figs. 4 and 5, where it is seen that the margins 40 of the upper are closely held in the peripheral groove, whereas the stitches pass up through the central portion of the shank and grip with its top-side in a manner adapted to hold the sub-stratum of leather bound together in a compact state; the strains from opposite sides being compensated for by opposing each other.

Besides the strength thus imparted to the shoe and to the shank, the interlocking stitching tends to hold the parts properly in their relative positions, thus avoiding any ready breakage of the shank while on the foot of the wearer, and also interposes a certain resistance to the turning of the heel under the foot of the wearer. It is also seen that the long narrow shank here employed merging 30 into the ball abruptly, provides an arrangement whereby the interlocking stitch may be conveniently applied over a relatively long length of shank. This is seen to be particularly facilitated by cutting the shank narrow and disposing the same so as to be offset from the centre line of the sole, whereby it abruptly joins the ball at 25.

The elliptical shaping of the seat requires in consequence a heel 15 somewhat in the shape of a truncated cone. This is seen to make for a relatively rigid heel adapted 190 better to support the weight and has a less thin portion at the shank of the shoe, which tends otherwise to receive excessive stresses and shear off.

A shoe having a sole to which an upper is secured in the manner described, is then turned, in order to complete the same. This completion is accomplished by first securing a metallic stiffening member as shown at 41, within the shoe along the shank that extends up into the heel; this metallic member being secured to a separate shank piece 42 that is placed in the shoe and secured to the sole by glue, nails or other convenient means. A sole lining 43 is then attached in the usual manner.

While the interlocked stitching here employed is described and shown as emerging from one face of the shank, i. e., the face of the shank next to the foot when the shoe is completed, it is seen that this stitching might equally well be arranged to emerge from the bottom of the shank shown in Figs. 4 and 5. Since this "one face" is merely relative and wholly a matter of choice in the finish of the shoe to be employed, the term "one face" is employed in the claims to describe either the top or bottom of the shank here employed.

Since certain changes may be made in the above construction and different embodi-

ments of the invention could be made without departing from the scope thereof, it is intended that all matter contained in the above description or shown in the accompanying drawing, shall be interpreted as illustrative and not in a limiting sense.

Having described my invention, what I claim as new and desire to secure by Letters Patent, is:

10 1. In shoe constructions of the character described, the combination with a sole having a ball portion, a shank portion, and a seat, said shank portion being relatively long and narrow, of an upper stitched to said sole, 15 said stitching entering said shank portion from opposite edges and emerging therefrom in interlocked formation on one face.

20 2. In shoe constructions of the character described, the combination with a sole having a ball portion, a shank portion, and a seat, said shank portion being relatively long and narrow, of an upper stitched to said sole, said stitching being a lock-stitch having a thread entering each of the opposite outer 25 edges of the shank and arranged to be interlocked along one face.

30 3. In shoe constructions of the character described, the combination with a sole having a ball portion, a shank portion, and a seat, said shank portion being relatively long and narrow, of an upper stitched to said sole, said sole being provided with a peripheral groove in which the margin of said upper is secured by a lock-stitch, said stitch 35 having threads entering said shank from opposite outer edges and interlocked along one face.

40 4. In shoe constructions of the character described, the combination with a sole having a ball portion, a shank portion, and a seat, said shank portion being relatively long and narrow, and offset from the centre line of the sole so as to meet the ball portion abruptly under the arch of the foot, said sole 45 being provided with a peripheral groove, of an upper, and a lock-stitch arranged to secure the margin of said upper in said groove, said stitch having threads entering said shank from opposite edges and interlocked 50 along one face.

55 5. In shoe constructions of the character described, the combination with a sole having a ball portion, a shank portion, and a seat, said shank portion being relatively long and narrow and offset from the centre line of the sole so as to meet the ball portion abruptly under the arch of the foot, of an upper, and a lock-stitch arranged to secure the margin of said upper to the edge of said 60 sole, said lock-stitch having threads entering the shank from opposite outer edges and arranged to emerge and interlock along one face.

In testimony whereof I affix my signature.
